BERT O. TILDEN, OF TRENTON, NEW JERSEY, ASSIGNOR TO AMERICAN SANITARY WORKS, OF TRENTON, NEW JERSEY, A CORPORATION OF NEW JERSEY.

WATER-CLOSET SEAT AND COVER HINGE.

1,248,949.

Specification of Letters Patent.

Patented Dec. 4, 1917.

Application filed August 1, 1917. Serial No. 183,954.

To all whom it may concern:

Be it known that I, BERT O. TILDEN, a citizen of the United States, residing at Trenton, in the county of Mercer and State of New Jersey, have invented certain new and useful Improvements in Water-Closet Seat and Cover Hinges, of which the following is a specification.

This invention relates to improvements in water-closet seat and cover hinges, and has for its object to provide a novel and simple hinge mechanism adapted for pivotally connecting closet seats and covers to the usual closet bowls, whereby a saving in the amount of metal comprising the hinges is effected and whereby the usual metal plates or leaves, which are invariably mounted on the exposed tops or bottom sides of the seats and covers and fastened thereto by screws, are eliminated. A further object is to provide a hinge structure in which the means for securing the hinge parts to the seat and cover are concealed and the top and bottom surfaces of the seat and cover are left free and clear, which renders the said part more sanitary—more readily cleaned and kept clean. A further object is to provide a hinge of the class which is so constructed and applied that when the seat and cover are lifted or swung upwardly away from the bowl they tend to stand erect or vertical of their own weight, and wherein the weight of the cover acts as a counter-balance for preventing either of said parts from accidentally falling upon the bowl. And a further object is to provide a "close roughing in" hinge structure which allows a water closet to be placed a shorter distance from the walls of a toilet than is possible by any other hinge mechanism known to me.

I attain these objects by the means set forth in the detailed description which follows, and as illustrated in the accompanying drawing, in which—

Figure 1 is a top plan view of a water-closet outfit, having my improvement applied thereto.

Fig. 2 is a side elevation of the same; showing by full and dotted lines the closed and open position of the seat and cover.

Fig. 3 is an enlarged broken side view; showing the hinge members and the seat and cover in different positions.

Fig. 4 is an enlarged broken rear elevation of the seat, cover and hinges. 55

Fig. 5 is a substantially vertical section taken on line 5—5 of Fig. 3.

Figs. 6 and 7 are respectively an edge and inner-side view of one of the hinge members common to both the seat and cover. 60

Fig. 8 is a view and modified form of hinge post which allows a greater roughing measurement than the straight posts in Figs. 2, 3, 4, and 5. 65

In the drawing, 2 represents a portion of the closet bowl, and 3 a "low-down" flush tank of conventional form, connected by a flush pipe 4.

5 represents a closet seat which may follow any of the usual constructions, but preferably has a reduced portion 6, at its rear end adjacent the tank 3. 7 represents the cover for the seat of somewhat smaller area, and which has a similar reduced rear end 8, preferably corresponding in breadth to the projection 6 of the seat. The opposite edges of the projections 6 and 8 are preferably parallel, as shown in Figs. 1, 4, and 5. 70

My improved hinge or hinges are disposed at the opposite rear corners of the closet seat and cover, and the exposed parts of the hinges are preferably entirely disposed at or on the lateral edges of the projections 6 and 8, and consist of the following parts: 9 represents similar hinge posts having ball-like heads 10, intermediate flanges 11 which rest upon the top surface of the closet bowl 2, and screw-threaded stems 12 which pass through suitable perforations 12' in the bowl. The posts 9 are preferably held in place by wing-nuts 13, and between the said nuts and the under surface of the bowl is usually disposed rubber washers 13'. The posts 9 are preferably straight and are 85 spaced apart sufficiently to loosely receive the reduced rear-end 6 of the seat 5, as best seen in Figs. 4 and 5. The heads 10 of the posts are provided with horizontal sockets 14, which face the said portion 6. 15 represents similar hinge members or plates, which are mounted so as to overlap the opposite lateral edges of the projections 6 and 8 of the seat and cover. Each member or bracket 15 has a perforation 16 near one end concentric to the socket 14 of the corresponding post 9. Each bracket 15 is provided on its inner surface with lugs or wings 17, 90

100

105

which are sunk into the material of the projection 6 of the seat (see Figs. 4, 5, 6, and 7), for the purpose of holding the said brackets rigidly in the proper position relatively to the seat and cover, as well as to render them movable with the seat. 18 represents pintles which pivotally connect the seat 5 to the posts 9. Each pindle 18 comprises a cylindrical head 18' which engages the socket 14 of the adjacent post, and a threaded portion 18'' which passes through the perforations 16 and is screwed into the reduced portion 6 of the seat. The pintles 18 being rigid in the seat, they turn in the sockets 14 whenever the seat is raised and lowered. When the bolts 18 are screwed into the seat the heads 18' being larger than the perforations 16, draw and rigidly hold the plates 15 tightly against the opposite edges of the seat. The pivot means for the cover consists of similar plain pins 19, which are preferably driven tightly into the opposite edges of the projection 8 of the cover, their outer free ends being inserted in sockets 20 formed near the opposite ends of the members 15 (see Fig. 5). By this construction and arrangement, the cover may be raised and lowered independently of the seat, by the pins 19 turning in the sockets 20. After the members 15 are applied to the lateral edges of the seat and cover, and the bolts 18 are screwed in tight, as shown and described, the seat and cover are securely connected to each other and may be rotated as one part on the pivot 14-18'. To apply the seat and cover to the closet bowl, the posts 9 are first slipped over the heads 18' of the bolts 18, then the threaded stems 12 of said posts are inserted downwardly through the perforations 12' in the closet bowl, and the wing-nuts applied, as shown.

The sockets 14 and the pindle heads 18' are preferably disposed substantially in the line of the longitudinal axis of the seat 5, as indicated by the broken line A in Figs. 4 and 5. When the seat 5 is raised to the vertical position shown in Figs. 2 and 3, the said axis A of the seat is directly in line 50 with the vertical axis A' of the posts 9 (see Fig. 3).

Heretofore, plumbers when making their "roughing in" measurements, frequently made the mistake of locating the pipes to 55 which the closet bowls are attached, too close to the walls of the toilets against which the flush tanks are disposed, to allow the seat and cover to be raised to the vertical or upright position, and to stand up alone, without some form of counter balance or weight to assist in holding them in the upright position. And in case the closet outfit were not provided with such counter weights, then when the seats and covers were both raised 60 at the same time, they had to be held, or

they would fall back upon the bowls. It is a particular object of my invention to do away with the extra counter weight attachments and preferably the "offset" posts, referred to, and also to provide closet seat and cover hinge mechanism which do not require such exact "roughing in" measurements, as heretofore, or which permit closer roughing measurements than formerly, whereby in case a mistake in such measurements is made, a closet bowl and tank may still be installed according to the measurements without relocating the floor pipes, and a cover and seat equipped with my improved hinge mechanism will stand upright without attention, or the aid of any extra parts. By referring to Figs. 2 and 3, it will be seen that both the seat and cover may be raised and left in the true vertical position and they will not fall accidentally. This result is attained by the peculiar shape of the hinge members 15 and the positioning of the same and the pintles 18-19 relatively to the seat and cover, as well as to the posts 9, as shown in the enlarged view in Fig. 3. When the seat and cover are disposed in upright position, the upper or free ends of the members 15 which support the cover 7, are tilted backwardly considerably beyond the main or fixed pivot center A', which is the center of the sockets 14 and the heads 18' of the pintles 18, and when the seat and cover are placed in this upright position, the weight of the cover is shifted an inch or more rearwardly of the said center A', which is enough to positively overcome the tendency of the seat, which is larger and heavier than the cover, to accidentally gravitate to the bowl. This feature is an important one, not only because it eliminates the extra counter weight parts referred to, and the extra expense and labor of applying such parts, but by its provision I am enabled to produce closet seat and cover hinges, which permit close "roughing in" as explained, and which are light and cheap, yet strong and durable. By the use of my improved hinge mechanism, a closet can be kept clean and sanitary and will stand long use, because there are no complicated or obstructing parts to hinder cleaning, and there are no screws or other attaching parts employed to split or otherwise mar or injure the material of the seat or cover. Owing to the damp conditions of toilets, the metal parts employed in and about water closets are preferably made of copper or brass, instead of iron or steel, which are liable to rust or otherwise deteriorate. It is also an object of my invention to provide closet seat and cover hinges which may be 120 constructed by the use of a relatively small amount of said metals, which tends to keep down the cost of such fittings.

In Fig. 8 I have shown a closet seat 5' which is pivoted by a pindle 14' in the head 130

of an off-set post 9', and a cover supporting plate 15 the same as in the preceding figures of the drawing. This view is important in that it shows the adaptability of my improved hinge mechanism to the old off-set or curved posts, wherein more liberal roughing measurements are obtainable.

Having thus described my invention, what I claim as new and desire to secure by Letters Patent, is—

1. A closet seat and cover hinge comprising a post having a socket, a threaded pintle having a head pivoting in said socket, a hinge member adapted to overlap a closet seat and cover having a perforation to receive said pintle and having a socket, and a pin rigid in the cover and pivoting in the socket of said member. 15

2. A closet seat and cover hinge comprising a bracket having a socket near one end and a perforation near the opposite end, a pin rotatable in said socket, a pintle inserted partway through said bracket having a cylindrical head, and a post having a 20 socket to pivotally receive said head.

3. A closet seat and cover hinge, comprising brackets overlapping the lateral edges of a closet seat and cover having sockets facing said cover and having perforations spaced from said sockets, pintles carried by the seat passing through and holding said brackets rigidly against the seat, and pins carried by the cover pivotally engaging the sockets in said brackets. 30

4. In closet seat and cover hinges, the combination with the seat and the cover, of brackets engaging the lateral edges of said seat and cover, means for pivotally connecting said cover between said brackets, a pair 35 of posts, and pintles screwed into the opposite lateral edges of said seat having heads pivotally engaging said posts and holding said brackets rigidly against the lateral edges of said seat.

5. The combination with a closet seat and cover, of a pair of hinge members overlapping the opposite lateral edges of said seat and said cover, said members having sockets facing said cover and having perforations registering with the lateral edges of said seat, pins carried by the cover pivoting in the sockets of said members, pintles passing through the perforations of said members, and screwed into said seat for 50 holding said members rigidly against the lateral edges of the seat, and posts having sockets to receive the heads of said pintles.

6. The combination with a closet bowl and a movable seat and cover, of a "close roughing in" hinge mechanism, comprising a pair 55 of hinge posts supported by said bowl, said posts spaced apart to receive a reduced portion of said seat and having sockets facing said seat, brackets engaging both the seat and the cover having sockets facing the

cover and having perforations registering with the sockets in said posts, pins supported by said cover and engaging the sockets of said bracket, and pintles screwed into the opposite lateral edges of said seat having 70 heads engaging the sockets of said posts and clamping said brackets to the opposite lateral edges of said seat.

7. The combination with the seat and cover, each having corresponding reduced 75 end portions, of a "close roughing in" hinge mechanism, comprising hinge posts spaced apart to receive the reduced end portion of said seat therebetween, brackets disposed between said posts and said seat and engaging the lateral edges of the reduced portions of said seat and cover, pintles passing through said brackets and into said seat for holding said brackets rigidly to and movable with said seat, said pintles having projecting heads engaging sockets in said posts, and means for pivotally connecting the opposite lateral edges of said cover to said brackets. 80

8. A closet seat and cover hinge, comprising hinge members overlapping the lateral edges of the seat and cover, said members rigidly secured to the seat and pivotally secured to the cover, posts for pivotally securing the seat and cover to a closet bowl, 95 said posts having sockets facing the opposite lateral edges of the seat and being in the line of the vertical axis of said posts, pintles driven through said hinge members and into the lateral edges of said seat in the line of the longitudinal axis of the seat, and having projecting heads which pivot in the said sockets adapted to support the rear portion of the seat and to allow said seat to be rotated from the horizontal to the 100 vertical position for bringing said horizontal axis in line with the vertical axis of said posts, the said hinge members adapted to support said cover when the seat and cover are standing upright in position to exert a 105 leverage for preventing the seat from falling. 110

9. In a water closet, a seat and cover hinge, comprising hinge plates overlapping the rear lateral edges of the seat and cover having perforations in line with the longitudinal axis of the seat and having sockets in line with the longitudinal axis of the cover, pins rigid in the cover and rotatable in said sockets, posts having sockets facing 115 the edges of said seat, and pintle-bolts passing through the hinge plates and screwed into the seat having projecting heads to engage the sockets of said posts. 120

10. In a water closet, a seat and cover 125 hinge comprising hinge plates overlapping the rear lateral edges of the seat and cover, pins rigid in the cover and pivoting in sockets in said plates, vertical posts having sockets facing the edges of the seat, pintles pass- 130

ing through said plates and anchored in said seat in the line of the longitudinal axis of the seat and having projecting heads rotatably received by the sockets of said posts, 5 and means for utilizing the weight of the cover for preventing the seat from falling from the upright to the horizontal position.

11. In a water closet, a seat and cover hinge comprising a pair of spaced posts 10 having sockets facing the lateral edges of the seat, hinge plates overlapping the rear lateral edges of the seat and cover, and rigid with said seat, said plates inclining

forwardly of the vertical axis of said posts when the seat and cover are in the horizontal 15 position and adapted to incline rearwardly of said axis when the seat and cover are in the upright position, whereby the weight of the cover overbalances the weight of the seat and prevents the seat from falling, means for pivotally connecting the cover to said plates, and means for pivotally connecting the seat to said posts.

In testimony whereof I affix my signature.

BERT O. TILDEN.
